UNITED STATES PATENT OFFICE.

JOHN KÖNIG, OF CLEVELAND, OHIO.

COLLAPSIBLE TABLE.

1,170,977.

Specification of Letters Patent.

Patented Feb. 8, 1916.

Application filed December 3, 1913. Serial No. 804,489.

To all whom it may concern:

Be it known that I, JOHN KÖNIG, a citizen of the United States, resident of Cleveland, county of Cuyahoga, and State of Ohio, have 5 invented a new and useful Improvement in Collapsible Tables, of which the following is a specification, the principle of the invention being herein explained and the best mode in which I have contemplated applying that principle, so as to distinguish it 10 from other inventions.

My invention relates to collapsible tables, its object being to provide a table light in structure and which may be folded into a 15 compact form for transportation or storage.

The said invention consists of means hereinafter fully described and particularly set forth in the claims.

The annexed drawings and the following 20 description set forth in detail certain means embodying my invention, the disclosed means, however, constituting but one of various mechanical forms in which the principle of the invention may be applied.

25 In said annexed drawings:—Figure 1 is a front elevation of a table embodying my invention, showing the parts in the position which they occupy when the table is set up. Fig. 2 is an end elevation of said table.

30 Fig. 3 is a front elevation of a table showing the parts in a position which they occupy while the same are being folded. Fig. 4 is a fragmentary longitudinal section upon an enlarged scale. Fig. 5 is a transverse section 35 taken upon the plane indicated by line V—V in Fig. 1, also on an enlarged scale. Fig. 6 is a perspective view of a fragmentary or detail portion of the table. Fig. 7 is a front view of the table in its folded or collapsed 40 form.

The illustrated embodiment of my invention includes in its structure three main parts, the top, the legs with their braces, and a stiffening or supporting truss.

45 The top consists of two parts 1, 1, each consisting of an upper member 2, two downwardly projecting side members 3, 3, and two downwardly projecting end members 4, 4. Each of these parts therefore forms a 50 box-like structure or receptacle open at the bottom when the table is in its extended or set-up condition. Adjacent to the inner surface of the abutting members 4, 4, are secured cross-pieces 5, 5, Figs. 4 and 5, and 55 secured to these cross-pieces respectively, are the hinges 6, 6, whose axes are in a straight

line perpendicular to the longitudinal axis of the table. The two parts 1, 1, are of the same dimensions and may hence be folded one upon the other so as to form a complete 60 inclosed receptacle, as shown in Fig. 7 and as will be readily understood.

Secured to the under surface of each part 1 and near the outer end thereof is a pair of blocks 7 and to these latter are hinged the 65 legs 8, the hinges being arranged so that the legs may swing inwardly, as shown in Fig. 3, against the under side of the corresponding top-part 1. The location of the hinges is also such that when these legs are so swung 70 they lie entirely within the parts 1 so that the latter may be closed upon each other without interference from within. Each pair of legs is provided with a transverse member 9, Fig. 2, to which are secured diagonal braces 10, and is furthermore provided with two additional diagonal braces 11, 11, as shown in Figs. 1 and 5, whose upper and inner ends articulate with suitable brackets 12 secured to blocks 13 which are themselves 80 suitably secured to the bottom of the members 2 of the parts 1. Each of these latter braces consists of two parts which are jointed, as shown in Fig. 6, the one part being provided with a stop 14 and the other with a 85 notch 15 adapted to be engaged by said stop whereby the two parts of each brace may be held rigid when in their operative position as shown in Fig. 1 and as will be readily understood.

90 Secured to the under side of the top of the table is a truss 16 which comprises the tension members 17, 17 and the compression members 18 and 19, these members being made preferably of suitable bars or strips 95 of metal. The outer ends of the tension members 17 are provided with an off-set portion 20, as shown in Fig. 3, and through this off-set portion passes a pivotal screw 21. The axes of these screws are in the same 100 straight line and preferably parallel with the top and sides of the table. The upper ends of the compression members 18 and 19 are similarly pivoted to the cross-piece 5, as shown in Fig. 4, by means of bolts 22, the 105 axes of these bolts being in alinement and coinciding with the line of the axes of the screws 21.

It will therefore be seen that the entire truss may be swung upon an axis and so as 110 to lie within the interior of the two parts 1, 1. An intermediate position of the truss

when being so swung is illustrated in dotted lines in Fig. 5. In order that the truss may lie completely within the parts as indicated, the location thereof is nearer one longitudinal edge than the other, as is also shown in said figure.

The inner and lower ends of each tension member 17 are secured to one leaf of a hinge 23 whose axis of oscillation runs in a direction 10 at right angles with respect to the direction of the axis of oscillation of the two parts 1, 1, of the top and this axis also lies in the vertical plane passing between the two abutting ends of these top parts. It 15 will therefore be seen that the truss consists of two parts hinged to each other, the hinge axis being perpendicular to the axis of oscillation of the truss. By means of this construction, the truss when lying within the 20 top part of the table may be folded with the two parts 1, 1.

In order to make the truss rigid when in its supporting or downwardly projecting position, the one compression member 18 has 25 hinged thereto a bracket 24 having an arm 25 extending transversely of the table, the upper end of this arm being adapted to engage a plate 26 secured to the member 2 of the corresponding part 1, as shown in Fig. 30 5. The axis of oscillation of this bracket lies in a pivotal rod 27 and is vertical. A coil-spring 28 surrounds this rod and one end thereof engages the compression member 18 and the other end engages the bracket 35 24. This spring is so arranged that it will tend to impart to the bracket its transversely extending position, illustrated in Fig. 5.

When it is desired to fold the table, the bracket 25 is first swung, against the action 40 of the spring 28, into a position parallel with the truss. The latter is then folded inwardly into the interior of the top of the table and the weight of the truss prevents the spring 28 from changing the position 45 of the bracket so imparted. The legs are then folded into the interior of the top and the two parts of the latter then folded upon each other so as to occupy the position 50 shown in Fig. 7. The legs are preferably made of wood and the braces 9 and 10 of suitable bar metal.

By means of the above-described arrangement of parts the top and legs of the table may be made very light, the truss 17 while

consisting of comparatively light members, 55 being exceedingly strong and efficient in its supporting function. Furthermore, as it will be seen, all of the parts may be completely inclosed within the top when the latter is in its folded position and may therefore occupy a comparatively small space as a result of which it may be easily transported or stored.

The outer or swinging ends of the parts 1, 1, may, when the table is in its collapsed or 65 folded position, be secured in any suitable manner, as for instance by means of a swinging hook 29 and headed pin 30 respectively secured to the ends of the two parts 1.

Having fully described my invention, what 70 I claim and desire to secure by Letters Patent is:—

1. In a collapsible table, the combination of a top; a truss comprising tension and compression members and having the outer 75 ends of its tension members and the upper ends of its compression members hinged to the under side of said top, the axes of oscillation of all of said members lying in the same straight line parallel with said top; 80 and an oscillatory member carried by one of said compression members adapted to be swung into position at right angles with said truss and to engage the under surface of the top, whereby said truss may be held 85 in its supporting position.

2. In a collapsible table, the combination of a two-part hinged top; a truss comprising two tension and two compression members; one tension and one compression member 90 being hinged to the under side of each part of said top, the axes of oscillation of all of said members lying in the same straight line parallel with said top when in its extended position; and a member having an 95 axis of oscillation perpendicular to the plane of the top of the table when extended, said member being mounted upon one of said compression members and including an arm adapted to engage the under surface of the 100 adjacent top member, whereby said truss may be held in its supporting position.

Signed by me, this 24th day of Nov., 1913.

JOHN KÖNIG.
